ADJUSTABLE CHAIR

Ernest Frederic Knauth, deceased, late of Brooklyn, N. Y., by Fifine O. Knauth, executrix, Brooklyn, N. Y.

Application May 28, 1937, Serial No. 145,377

3 Claims. (Cl. 155—28)

This invention appertains to new and useful improvements in furniture and more particularly to an adjustable chair, the principal object being to provide a chair which can be readily adjusted to various positions so that various massaging or other therapeutic treatments can be conveniently and efficiently given to patients resting thereon.

Another important object of the invention is to provide an adjustable reclining chair upon which a patient can rest and be supported in substantially any degree of reclination, with the least amount of effort on the part of the patient or the operator.

Other important objects and advantages of the invention will become apparent to the reader of the following specification.

In the drawings:

Figure 1 represents a vertical sectional view taken substantially on the line 1—1 of Figure 2. Figure 2 represents a front elevational view of the chair showing a portion broken away.

Figure 3 is a top plan view of the cradle.

Figure 4 is a sectional view taken substantially on the line 4—4 of Figure 1.

Figure 5 is a fragmentary front elevational view of the chair showing the connection between the back sections.

Referring to the drawings wherein like numerals designate like parts, it can be seen in Figures 1 and 2, that the chair consists of a pair of sturdy side walls 5—5. At the inner side of each of these side walls 5 is an angle iron member having a pair of upstanding post member sets 7—8, the post members being connected by the elevated bridge piece 9, upon which the forward end of the seat section 10 can rest when in a horizontal position.

Hingedly connected as at 11 to the forward end of the seat section 10 is the leg section 12 to the bottom side of which the rack bar 13 is pivotally connected as at 14. This rack bar 13 being disposed through the slotted plate 15 which is connected as at 11 to the bridge piece 9 as shown in Figure 1, the teeth of the rack bar 13 being engageable with the plate 15 at the lower end of the slot therein for fixing the leg section 12 at any desired adjusted position with respect to the main seat section 10.

It will be observed in Figure 1 that rearwardly of the intermediate portion of the seat section 10 a shaft 16 is provided, the end portions of which are journaled in the upper ends of the post 8. Thus the rear portion of the seat section 10 is supported by the shaft 16 while the

forward portion is supported by the bridge piece 9. A frame structure 17 is hingedly connected as at 19 to the rear end of the seat section 10 and slidably disposed in this frame 17 are the lower back cushions or sections 18 and the upper cushions or sections 19, the upper sections 19 being connected to the lower sections 18 by pins 20 (see Figure 2).

On the side members of the frame 17 are the barrels 21 in which the rods 22 are slidable, a set screw or other suitable detent 23 being carried by each of these barrels 21 whereby the rods 22 can be secured in a definite adjusted position with respect thereto.

Padded or upholstered shoulder-embracing members 24 are hingedly connected as at 25 to the forwardly disposed end portions 26 of the rods 22 and a set screw 27 can be provided at the connection 25 for fixing the corresponding shoulder-embracing member in position for holding a patient firmly yet not uncomfortably against the chair back.

The cradle for the chair assembly is generally referred to by numeral 28 and consists of the L-shaped bars 29—29, shafts 30—31 are provided at the respective ends thereof and on these the rollers 32—32 and 33—33 respectively, are located.

A plate 34 bridges the L-shaped bars 29—29 and this plate is provided with depending ribs 30—35 at the longitudinal edge portions thereof so that the plunger rod 36 of the hydraulic jack 37 will always remain against some portion of the plate 34.

It can be seen that posts 38 support the cradle 28 by the cross-rod 39 and that by releasing the jack 37 and allowing the chair assembly to swing rearwardly of its own weight and the patient's against the same, the cradle will rock so that the forward rollers 33 will engage the bottom of the seat section 10 as it leaves the bridge piece 9 while the back section will engage against the rear rollers 32. Thus, the leg section 12 when properly adjusted with respect to the seat section 10, and the back section can be moved as a couch section and swung to any degree of inclination desired without discomfort to the patient or inconvenience to the operator.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

1. A chair structure comprising a seat member, means supporting said seat member including means suitably mounting the same upon a horizontal axis, a back rest pivoted to said seat for swinging movement from a normal upright position downwardly into alignment with said seat member, means for tilting said seat member and for supporting said seat member and said back rest in various tilted positions comprising a cradle member having a pair of rigidly connected divergent leg portions extending forwardly and rearwardly of said chair structure respectively beneath the seat member and rearwardly of the back rest, forward and rearward support members in engagement with a leg of said cradle, one of said support members providing a fixed axis pivotally mounting said cradle for swinging movement in a vertical plane, said other support member being adjustable in height to hold said cradle in selected adjusted positions whereby said leg portions may be brought into engagement with said pivotally mounted seat member and said back rest to adjust the same in various angular relations, said adjustable support including fluid operating means for effecting adjustment.
2. A chair structure comprising a seat member, means supporting said seat member including means suitably mounting the same upon a horizontal axis, a back rest pivoted to said seat for swinging movement from a normal upright position downwardly into alignment with said seat member, means for tilting said seat member and for supporting said seat member and said back rest in various tilted positions comprising a cradle member having a pair of rigidly connected divergent leg portions extending forwardly and rearwardly of said chair structure respectively beneath the seat member and rearwardly of the back rest, forward and rearward support members in engagement with a leg of said cradle,

one of said support members providing a fixed axis pivotally mounting said cradle for swinging movement in a vertical plane, said other support member being adjustable in height to hold said cradle in selected adjusted positions whereby said leg portions may be brought into engagement with said pivotally mounted seat member and said back rest to adjust the same in various angular relations, said adjustable support including fluid operating means for effecting adjustment.

3. A chair structure comprising a seat member, means supporting said seat member including means suitably mounting the same upon a horizontal axis, a back rest pivoted to said seat for swinging movement from a normal upright position downwardly into alignment with said seat member, means for tilting said seat member and for supporting said seat member and said back rest in various tilted positions comprising a cradle member having a pair of rigidly connected divergent leg portions extending forwardly and rearwardly of said chair structure respectively beneath the seat member and rearwardly of the back rest, forward and rearward support members in engagement with a leg of said cradle, one of said support members providing a fixed axis pivotally mounting said cradle for swinging movement in a vertical plane, said other support member being adjustable in height to hold said cradle in selected adjusted positions whereby said leg portions may be brought into engagement with said pivotally mounted seat member and said back rest to adjust the same in various angular relations, said cradle being in the form of a frame including side members and a cross member for the frame, said adjustable support being engaged with the said cross member.

FIFINE O. KNAUTH,
*Executrix of the Last Will and Testament of E. 40
Frederic Knauth, Deceased.*
